[57] CLAIM

The ornamental design for an elephant head drinking cup, as shown.

DESCRIPTION

FIG. 1 is a perspective view of an elephant head drinking cup, embodying my new design, and showing the front, top and right sides thereof;

FIG. 2 is a left side elevational view thereof, the right side being a mirror image of the left side as shown;

FIG. 3 is a front elevational view thereof;

FIG. 4 is a rear elevational view thereof;

FIG. 5 is a top plan view thereof;

FIG. 6 is a bottom plan view thereof; and,

FIG. 7 is a vertical sectional view taken generally on the line 7—7 of FIG. 3.

FIG. 1

FIG. 2

FIG. 3

FIG. 4

FIG. 5

FIG. 6

FIG. 7
